UNITED STATES PATENT OFFICE.

ROBERTO TAEGGI PISCICELLI, OF NAPLES, ITALY.

ELECTRIC TELPHER POSTAL SYSTEM.

No. 828,678.

Specification of Letters Patent.

Patented Aug. 14, 1906.

Application filed September 5, 1902. Serial No. 122,305.

To all whom it may concern:

Be it known that I, ROBERTO TAEGGI PISCICELLI, engineer, a subject of the King of Italy, and a resident of Naples, Italy, Corso Umberto I, No. 23, have invented a new 5 Electric Telpher Postal System, of which the following is a full, clear, and exact description.

The object of the present invention is to 10 provide mechanical devices, acting for the most part automatically, by means of which the correspondence introduced in the posting-boxes erected in various and distant points of a postal district is rapidly collected 15 and carried to the central office. To obtain this effect, the collection of the correspondence is effected by means of small vehicles driven by electric motors and running over special aerial lines used exclusively for this purpose 20 and made of insulated metallic wires or cables, which act as guides to the vehicles and as conductors of the electric current.

Reference is to be had to the accompanying drawings, forming a part of this specification, in which similar numerals of reference 25 indicate corresponding parts in all the figures.

Figures 1 and 2 show, respectively, a side elevation and a plan of a collecting-box; Fig. 3, a vertical section of a collecting-pole; Figs. 4, 5, and 6, two sectional views at right angles of the base of a collecting-pole and a plan view of the same on a large scale. Figs. 7 and 8 show, on a large scale, the details of the 35 top of the collecting-pole. Fig. 9 is a plan of the above. Fig. 10 is a diagram of the connections of the low-potential line, over which the collecting-boxes run, the motor driving the post-box, and the commutator. Figs. 11 40 and 12 show in elevation and plan the arrangement of the levers causing the commutator to act. Figs. 13, 14, and 15 are respectively side, front, and plan views of the electric commutator causing the movement of 45 the post-box. Fig. 16 shows diagrammatically the connection of the posting-boxes with the central station.

The central post-office 63 is connected to the posting-boxes 64, erected in the limits of 50 the postal district for the convenience of the public, by means of aerial lines, over which run the "collecting-boxes." Each line starts from the central post-office, connects several posting-boxes, and goes back to 55 the central station, thus accomplishing its round. The service of the collecting-boxes

should be regulated in such a manner as to never allow more than a single vehicle being at one time on each line in order to prevent any shock between two collecting-boxes running on the same line.

The lines are fed by a low-potential three-phase current from transformers placed at the central post-office, which avoids the necessity for the line whereon the vehicles run 65 to be accompanied by a high-potential line.

Every line consists of only three metallic wires, two, 1 1', Figs. 1 and 2, on the higher level, and one, 2, on the lower one, all acting as conductors of the electric current and at 70 the same time as supporters of the wheels of the vehicles. The current passes from the three wires of the line to the motors through the wheels of the vehicles and the contact-roller fixed on the lower part of the box.

The parts 65 of the lines at their end near the central office and those including a post-collecting pole are deprived of current, owing to the collecting-boxes having to stop successively above each post-collecting pole, and at 80 the end of their run in the central office. To cut off the current from each of such parts of the line, it will be enough to electrically insulate the ends of the two conductors, over which the wheels of the vehicles are running, 85 at the two poles supporting such parts, because it suffices to interrupt two of the conductors to prevent any current passing on the line. Finally in order that the two parts of the line immediately preceding and 90 following the above-insulated part may be fed by current it will be enough to connect, by means of independent wires 66, the ends of the two parts of the line comprising the insulated conductor.

A collecting-box consists of a rectangular frame 3, supported on four wheels 4 4 5 5, Figs. 1 and 2, which run over the two higher wires 1 1' of the line. The two fore wheels 4 are of a larger diameter and keyed on the 100 axle of the electric motor 6 and act as driving wheels, while the two back ones, 5, act only as guides. The longitudinal bars of the frame 3 are fitted with bosses 7, on which two pivots are screwed, the ends of which support the 105 box 8.

The collecting-box in the shape of a prolonged pyramid body is open on top and hangs between the two above-mentioned bars. It is so balanced that it has a constant tendency to place itself in a vertical position, which it assumes on arriving above a

post-collecting pole. Furthermore, the box is fitted with a small roller 9, fixed under its bottom and intended to rest upon the third wire 2 of the aerial line. The distance, however, of said small roller from the points of suspension of the box is greater than that between said points and third lower wire 2 of the line. It is evident, therefore, that when the collecting-box passes from the inflexible 10 rails above the post-collecting pole to the wires it will necessarily leave its vertical position and resume its inclined position. The fore part of the box will thus enter a metallic cover 10, fixed on the rods connecting the 15 wheels of the vehicle, which is so shaped and disposed as to fit the box just like a fixed cover would do, thus preventing rain-water from entering. Further, in order to render the closing perfectly tight, the fore part of 20 the box is fitted with a flange 11, fitting the cover and leaving no interval through which rain could percolate into the box.

A post-collecting pole, as seen in Fig. 3, consists of an iron column 12, covered with 25 iron plates to prevent rain entering. By means of steps placed on one of its sides a workman can go up to inspect the mechanism, and by means of small doors on one of the faces of said column he can look inside it.

30 Inside the collecting-poles are arranged various devices which are hereinafter particularly described.

First. The box 13 for ordinary letters posted by the public, running in the collecting-pole, which will be hereinafter referred to as the "posting-box," is moved by a steel-wire rope 14, guided by two grooved pulleys, one of which, 15, is placed at the bottom of the pole, and the other, 16, at its top. It is 40 evident that the posting-box will be compelled to go up or down, according to the direction of the pull exerted on the steel rope. In its normal position the posting-box remains at the bottom of the pole and at such a level 45 as to allow letters to drop into it after they have passed through the posting-opening. The posting-box is connected with the rope by a frame 17, to which it is pivoted below its center. The box is guided up and down 50 by four small guide-rolls 18, as shown in Figs. 4 5 6. These rolls run over guides 19, which widen out at their highest points, compelling the posting-box to turn over and drop the correspondence into the collecting-box 8 through a hopper 20.

Second. The motor 21 (seen in Fig. 5) is a small three-phase electric motor driving the lower pulley 15, over which runs the rope 14, hoisting the posting-box. The connection 55 between the motor 21 and the pulley 15 consists of gear-wheels for reducing the speed. One terminal 22 of the motor (see Fig. 10) is in uninterrupted communication with the third wire 2 of the line. The other two are 60 in communication with a commutator 23,

situated on the top of the pole. These last two terminals can be connected one way or the other with the wires 1 1' of the aerial line, causing the motor to revolve either way.

Third. The head of the collecting-pole (see 70 Figs. 7, 8, and 9) has two rails 24 slightly inclined forward, to which are joined the line-wires 1 1'. Each of these rails is made of two U-shaped irons, with an interval between them. The lower wire 2 is cut off in order to 75 allow the collecting-box, when on the top of the collecting-pole, to place itself in a vertical position. Furthermore, there is in the top of the post-collecting pole the following apparatus: The automatic stop for the collecting-boxes, acting only when one of them is 80 arriving at the collecting-pole, a starting apparatus for the collecting-boxes after they have taken in the correspondence; an electric commutator 23 for controlling the motor 85 driving the posting-box.

The stop intended for stopping automatically the collecting-box when it arrives at the collecting-pole is composed of two blocks 25, each of them sliding in a vertical plane 90 parallel to the rails in the intervals between the two U-shaped irons. The wheels of the collecting-box are stopped when the two blocks rise over the rails. Another part of the stop consists of two pieces 26 in the intervals of the rails, which being controlled by springs 27 are depressed on the arrival of a collecting-box and afterward rise again, thus preventing it from going back at the moment it shocks against the blocks 25. The two stops 95 when in their usual position rise up above the rails and are kept so by levers 28, with counterweights 29 preventing an arriving box from running farther. They can, however, be mechanically lowered. To do this, there 100 is a contrivance consisting of two pulleys 30, keyed on a single axle 31, having keyed on its end a counterweight-arm 32, the movement of which is limited. On these two pulleys are wound two thin steel-wire ropes 33, running over guide-pulleys 34 and tied to the blocks 25. When the axle 31 turns, the pulleys 30 wind up the ropes 33, and the blocks 25 are compelled to move downward in their guides, clearing the way. There is on the 105 axle 31 a lever 35, tied by a rope 36 to an arm 37, turning on a pivot 38. It is evident that when pressure is exerted from below on the end 39 of the lever 37 the tension of the rope 36 will cease, and therefore no movement of 110 the lever 35 will take place. If, on the contrary, a pressure is exerted from above on the end 39 of the lever 37, the lever 35 will be lowered. Thereby the axle 31 causes the pulley 30 to turn and the blocks 25 to go 115 down. A lug 40 (see Figs. 4 and 6) is fixed on one of the faces of the posting-box 13, so as to meet the end 39 of the lever 37 when the posting-box goes up or down. It is evident, therefore, that when the posting-box 120

goes up the lug 40 meeting the end 39 of the lever 37 causes no movement of the axle 31. When, however, the posting-box goes down, the end 39, encountering the lug 40, compels 5 the levers 37 and 35 to describe a more or less large angle, according to the length of the end 39. When the posting-box, after having dropped its letters into the collecting-box, has started on its downward run, it will dis- 10 engage the wheels of the collecting-box, which can then resume its travel toward the next collecting-pole.

Although owing to the inclination of the aerial way the collecting-box should start as 15 soon as the two blocks are lowered, nevertheless to make quite sure an apparatus has been added to secure such a starting. This apparatus consists of two levers 41, moving on pivots 42 and which strike the axle of the 20 two back wheels 5 of the collecting-box. To obtain this result, the levers 41 are balanced by counterweights 43 and rest by their ends against two small pulleys 45. On these pulleys are cavities into which the ends 44 enter 25 when the pulleys 45 revolve, and then the counterweights 43 compel the levers 41 to strike the axle of the wheels 5. These pulleys are so keyed on the axle 31 that they actuate the levers 41 soon after the lowering of 30 the blocks 25. The counterweights 32 bring back the axle 31 and the pulleys 30 and 45 as well to their normal position.

As already stated, the motor driving the posting-box is to receive the current twice, 35 once when the box goes up and again when it goes down. For this purpose the post-collecting-pole is fitted (see Figs. 10, 11, 12, 13, 14, and 15) with the commutator 23, consisting of a small ebonite cylinder 46, on the axle 40 of which a toothed wheel 47 is keyed. A lever 48 moves on an axle 49, and has on it a click 50. When the lever 48 is rocked, the click 50 will cause the wheel 47 to turn round at intervals, and thereby the ebonite cylinder 45 turns as well. On the ends of the ebonite cylinder 46 two metallic rings 51 are fixed, on 50 which two brushes 52 rub. These brushes are in electric communication with the two conductors 1 1' of the aerial line. On the middle part of this cylinder are contact-pieces 53, in communication with the rings, as seen in Fig. 10. Two other brushes 54, connected with the terminals 55 55' of the motor 21, driving the posting-box, touch the contact-pieces. It is evident, therefore, that when the ebonite cylinder 46 turns round then at a certain moment the two conductors 1 1' of the line are respectively in communication with the two terminals 55 55' of the motor. 60 On the cylinder continuing to turn round the conductors of the line will be cross-connected with the motor terminals—viz., 1 with 55' and 1' with 55. Such a motion still continuing the middle brushes will touch the ebonite part of the cylinder and thereby the circuit

between the line and the motor will be cut. The third conductor 2 of the line is always, as stated, connected to the third terminal 22 of the motor. When a collecting-box reaches a collecting-pole, one of the pieces 26 in its 70 downward movement causes the lever 56 to raise the rod 57, the upper end of which is forked. This fork will raise the lever 48, and then the click 50 causes the cylinder 46 to turn, so that the brushes 54 contact with the pieces 75 53, and consequently a communication between the conductors 1 1' of the line with the terminals 55 55' is established, and therefore the posting-box 13 goes up. When the posting-box arrives at the top of the collecting- 80 pole, it turns over and hits a rod 58, which causes the cylinder 46 to again turn, and the motor revolves in the contrary direction, causing the posting-box to go down. Lastly when the posting-box reaches the lowest 85 point of its downward course, a finger 59, on the rope 14, rocks the levers 60 61, which depresses the rod 62. This by striking the lever 48 causes the commutator to turn further, and the brushes 54, coming onto the ebonite, will break the contact and stop the motor. The commutator having now performed half a revolution is in such a position as to be ready to act on the arrival of another collecting-box.

I claim—

1. In an electric telpher postal system, the combination with the aerial lines, the several collecting-poles connected by said lines, the lines having insulated sections before the collecting-poles, of the conducting-wires which connect the sections preceding and following the insulated ones.

2. Collecting-boxes for use in an electric postal system, consisting of a frame 3 with 105 two pairs (4, 5) of wheels, a three-phase motor 6 driving one pair 4 of said wheels, a cover 10 for the letter-box 8 fixed on said frame, said box 8 hanging in the frame 3 and resting on a lower contact-roller 9, substantially as 110 described.

3. Collecting-boxes for use in an electric postal system, consisting of a frame with four wheels, running on the two upper wires 1, 1' of the aerial lines connecting the collecting-poles, a three-phase motor 6 on the axle of which are directly keyed the fore wheels 4 of said frame 3, acting as driving-wheels and contact-rollers, and a letter-box 8 kept closed when running by means of the third wire 2 of 115 the line, but opening by gravity when the support of this third wire is removed, substantially as described.

4. Collecting-poles containing a posting-box 13 a motor 21 actuating same and a commutator 23 controlling the motor and actuated by the arrival of a collecting-box, substantially as described.

5. In an electric telpher postal system, the combination of a collecting-pole, a posting- 130

box 13, a frame 17 to which the box is pivoted near the bottom, rollers 18 on the box, and vertical guides on the collecting-pole in which the rollers run, which guides widen out at their highest points and compel the box to turn over on reaching the top of the pole, substantially as described.

6. In an electric telpher postal system, the combination with the collecting-poles, the rails supported on said poles, and the pivoted spring-brakes 26, of two sliding blocks 25, and means by which said blocks are normally maintained projecting above the rails, for the purpose set forth.

7. In an electric telpher postal system, the combination with the collecting poles, the aerial line connecting said poles and having the upper wires 1, 1', and the lower wire 2, and the pivotally-mounted collecting-boxes which run on said wires, of rails at the top of the poles connected with the upper wires 1, 1' of said line, the lower wire of said line being interrupted at a point corresponding with the rails to allow a collecting-box to assume a vertical position, for the purpose set forth.

8. In an electric telpher postal system, a collecting-pole, provided with a pivotally-mounted and vertically-movable posting-box, guides for said posting-box arranged to permit the box to turn over when it reaches the top of the pole, line-wires connected with the pole, a collecting-box which runs on the line-wires, a three-phase motor 21 driving the posting-box, a commutator for said motor comprising a cylinder 46 of insulating material, fitted with two metal rings 51, brushes 52 in permanent contact with said rings, and in electric communication with the upper wires 1, 1' of the line, two series of contact-pieces 53 alternatively communicating with the two rings 52, brushes 54 to make contact with said pieces and in communication with the terminals 55, 55' of the motor, a ratchet-wheel 47 keyed on the axle of the cylinder 46, a rocking lever 48 with a click 50 which rotates the ratchet-wheel and the cylinder, thus crossing or interrupting the connections between the terminals of the motor and the wires of the line, and suitable connections by means of which the collecting-box on reaching the pole, and the posting-box on being turned over and on reaching its lowest position at the base of the pole, rocks the lever and rotates the cylinder.

9. In an electric telpher postal system, the combination with the aerial lines, and the collecting-poles, of a self-propelled collecting-box 8, which stops at each collecting-pole, rails at the top of the collecting-pole, pivoted spring-brakes 26 normally projecting above the rails, a motor 21, a commutator 23 for inverting or interrupting the current in the motor, a cylinder with contact-pieces rotatably mounted in said commutator, a rocking

lever 48 for rotating said cylinder, and suitable connections between the rocking lever 48 and the spring-brakes 26 for the purpose of rocking the lever and rotating the cylinder of the commutator when the collecting-box stops at the top of the pole.

10. A collecting-pole for use in an electric telpher postal system, comprising a pivotally mounted posting-box 13, vertical guides 19 in which the box is movable, a motor 21 for lifting said box, the said guides being widened at their highest point to allow the box to turn over on its arrival at the top of the pole, a rod 58 against which the box strikes in turning, a commutator 23 for inverting or interrupting the current in the motor, a rocking lever 48 and a rotatable cylinder 46 forming part of said commutator, and suitable connections between the lever 48 and the rod 58 by means of which the lever is rocked and the cylinder rotated when the box is turned over.

11. A collecting-pole for use in an electric telpher postal system comprising a commutator 23 at the top of the pole, a motor 21 at its base, a posting-box 13, a hoisting-rope 14 for the box actuated by the motor, a lug 59 fixed on the hoisting-rope, a rocking lever 48 and a rotatable cylinder 46 forming part of the commutator, and suitable transmission means by means of which the lug 59 operates the rocking lever 48 of the commutator and rotates the cylinder 46, on the posting-box reaching its lowest position at the base of the pole.

12. In the collecting-poles of an electric telpher postal system, the combination of projecting blocks 25, launching-levers 41, a posting-box 13 movable vertically, a hoisting-rope 14 for supporting the same, a lug 40 on the posting-box, and a swinging arm 37 adapted to be hit by the lug 40 during the descent of the posting-box, the said arm, when hit by the lug, first depressing the projecting blocks and then operating the launching-levers.

13. In an electric telpher postal system, the combination with a collecting-pole, and the aerial line, of a collecting-box which runs on the aerial line, a posting-box having vertical movement in the collecting-pole and mounted to turn to deliver the mail to the collecting-box when the latter reaches the pole, a device for stopping the collecting-box at the pole, means controlled by the movement of the posting-box, for moving said stopping device to release the collecting-box, and means also controlled by the movement of the posting-box, for starting the collecting-box when released.

14. In an electric telpher postal system, the combination with the aerial line, and the collecting-poles connected to said line, of a collecting-box which runs on said line, a post-

ing-box movable vertically in each collecting-pole, a motor for actuating said posting-box, a commutator for said motor, suitable electric connections between the commutator and the motor and the commutator and the line, a rocking lever connected with the commutator, a device engaged and moved by the collecting-box on its arrival at the collecting-pole, and a connection between the said device and the rocking lever of the commutator whereby the commutator is moved to start the motor.

15. In an electric telpher postal system, the combination with a pivotally-mounted posting-box, guides in which the box has vertical movement, a motor for lifting said box, the said guides spreading at their upper ends to permit the box to turn on its pivot, a commutator for the motor, and mechanism for moving the commutator to reverse the movement of the motor, the said mechanism being

operated by the box when the latter turns on its pivot.

16. In an electric telpher postal system, the combination with a collecting-pole, of a motor, a commutator for the motor, a posting-box having vertical movement in the collecting-pole and actuated by the motor, a rocking lever for the commutator, and means whereby the rocking lever of the commutator is operated, when the posting-box reaches its lowest position at the base of the pole, to move the commutator to stop the motor.

In testimony whereof I have signed this 35 specification in the presence of two subscribing witnesses.

ROBERTO TAEGGI PISCICELLI.
